UNITED STATES PATENT OFFICE.

D. CUMMING, JR., OF NEW YORK, N. Y.

IMPROVED LOOKING-GLASS AND MATCH-HOLDER.

Specification forming part of Letters Patent No. 39,277, dated July 21, 1863.

To all whom it may concern:

Be it known that I, D. CUMMING, Jr., of New York, county and State of New York, have invented a new and improved article of manufacture consisting of a looking-glass combined with a match-holder and friction-surface; and I do hereby declare that the following is a full, clear, and exact description of the construction and operation of the same, reference being had to the annexed drawings, making a part of this specification, in which—

Figure 1 is a front elevation; Fig. 2, a vertical section.

The same letters refer to corresponding parts in the different figures.

A is the frame of the looking-glass B, to which are attached the match holders C C and friction-surfaces D D.

In using the above invention the frame is hung on the wall so that matches may be

taken from the holders and ignited by rubbing them on the friction-surfaces.

The above invention can be manufactured at a small cost above an ordinary looking-glass of the same size, and by using the frame for a friction-surface a much larger surface is obtained than that usually on match-holders, thereby preventing the walls of rooms and furniture from being injured by rubbing matches on them.

What I claim as new, and desire to secure by Letters Patent, is—

A new article of manufacture consisting of the combination of a looking-glass with a match holder and friction-surface, constructed substantially as herein set forth.

D. CUMMING, JR.
